CLAIM

I claim the ornamental design for a brace shoe for a concrete panel brace, as shown and described.

DESCRIPTION

FIG. 1 is a front, top, and right side perspective view of a brace shoe;

FIG. 2 is a rear, top, and left side perspective view thereof;

FIG. 3 is a rear elevation view thereof;

FIG. 4 is a front elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines shown in the drawings depict environmental structure and form no part of the claimed design.
